CLAIM

The ornamental design for a cable protector, as shown and described.

DESCRIPTION

FIG. 1 is a perspective view of an embodiment of a cable protector;

FIG. 2 is a front view of the cable protector shown in FIG. 1;

FIG. 3 is a rear view of the cable protector shown in FIG. 1; FIG. 4 is a left-side view of the cable protector shown in FIG. 1;

FIG. 5 is a right-side view of the cable protector shown in FIG. 1;

FIG. 6 is a top view of the cable protector shown in FIG. 1; and,

FIG. 7 is a bottom view of the cable protector shown in FIG. 1.

The cable protector is shown with a symbolic break in its length. The appearance of any portion of the article between the break lines forms no part of the claimed design. In the drawings, the broken lines are for the purpose of illustrating portions of the cable protector which form no part of the claimed design.
